UNITED STATES PATENT OFFICE

FRANCIS R. McINTYRE, OF OGDEN, IOWA

COVER FOR FUEL TANK OPENINGS

Application filed December 22, 1930. Serial No. 504,037.

This invention relates to the removal of inflammable fuel from railway tank cars in which a vertically arranged pipe is usually inserted in the manhole, said pipe extending 55 downwardly into the tank to a point near its bottom and detachably connected to a suitable pump pipe.

On account of the manhole opening of the tank being larger than the pump pipe, it will 10 readily be seen that a comparatively large open space exists around the pipe through which particles of dirt and hot cinders may enter. The hot cinders sometimes set fire to the fuel within the tank, causing the loss 15 of human life.

To overcome the possibility of such accidents, the operators are required to stuff the space around the pipe with water soaked burlap or similar material, so that any hot 20 cinders will be excluded from the interior of the tank and extinguished by engaging the wet burlap.

The use of the water soaked burlap is very 25 undesirable for the reason that in the winter it freezes and it is almost impossible to use it with any degree of satisfaction. In warmer weather, the water soaked burlap is often stored away in some corner of a building and often causes fire by spontaneous combustion. 30 Furthermore, the wet burlap is unhandy and often is not used.

It is, therefore, the object of this invention 35 to provide simple and inexpensive means, which is always accessible and which may be easily and quickly applied to the manhole opening at the time the pump pipe is placed therein, which is practically fireproof and will not freeze.

More specifically it is the object of my invention 40 to provide a cover of pliable material which may be adjustably mounted on the detachable portion of the pump pipe, so arranged that it may be open to a substantially cone shaped form to completely cover the opening, and to permit hot cinders and particles of dirt to roll off of its surface by gravity, and at the same time provides means whereby the cover may be easily and quickly 45 folded into compact form.

50 This invention consists in the construction,

arrangement and combination of the various parts of the device, whereby the objects contemplated are attained, as hereinafter more fully set forth, pointed out in my claims, and illustrated in the accompanying drawing, in which:

Figure 1 is an end elevation of a tank car showing the manner in which the pump pipe is applied thereto while emptying the car, and the manner in which my improved cover 60 is applied to the pipe and the tank.

Figure 2 is a detail sectional view taken on the line 2—2 of Figure 1.

Figure 3 is a detail sectional view taken on the line 3—3 of Figure 2.

Figure 4 is an enlarged side elevation of my improved cover in a folded position, as applied to the pump pipe.

Figure 5 is a detail sectional view of the upper end of the cover as applied to a segmental portion of the pump pipe.

In the accompanying drawing, I have used the reference numeral 10 to indicate the railway car on which is supported a fuel tank 11 of ordinary construction, having an upwardly projecting drum portion 12 in its upper side. The head 13 of said drum is provided with a manhole opening 14.

A cover plate is always provided for the manhole opening, which is fixed in position 80 to cover the opening during transportation, said cover being removed at the time it is desired to remove the fuel. Said cover is not here illustrated inasmuch as it forms no part 85 of this invention.

Supported horizontally above the tank 11 is a pump pipe 15, also of ordinary construction, and provided with pumping means not illustrated for drawing fuel out of the tank 11. The pipe 15 is provided with an elbow 90 portion 16 having a flange 17 to which a similar flange 18 is secured by means of suitable bolts 19. The flange 18 is designed to support a pipe 20, the lower end of which projects downwardly into the tank 11, terminating near the bottom of said tank.

My improved cover comprises a substantially cone shaped member 21, preferably formed of pliable material, such as canvas, and having its base edge provided with a hem 100

22 to form a reinforcement for said edge. The hem portion is provided with a series of perforations 23 adapted to receive ropes or other similar devices by means of which the 5 lower edge of the cover may be tied down if so desired. Ordinarily I find that the use of tie strings is not necessary.

The apex end of the member 21 is provided with an opening 24 for receiving the pipe 20. 10 The said opening 24 is reinforced by a collar 25, which is also formed of pliable material such as canvas, formed by doubling the material one or more times upon itself, and sewing the folded portions together, then forming 15 the folded member into a ring or collar which is placed inside of the opening 24 and stitched to the member 21. The collar 25 is then slid on the pipe 20 to a point near its upper end and secured in position by means of a metal 20 clamp 26, having a bolt 27 and a thumb nut 28 for applying tension to the clamp, whereby the cover member may be slidably mounted on the pipe 20 to accommodate tanks of various elevations.

25 The binding cord 29 is provided, the central portion of which is fixed to one side of the member 21, with both ends free, in such a manner that the cover may be folded around the pipe and finally tied in the manner clearly 30 illustrated in Figure 4.

The pliable material from which the cover is formed is treated with fireproofing material, so that any hot cinders or the like falling on the cover will not cause the cover to burn.

35 In practical operation the pipe 20 is detached from the pipe 15 when not in use. When it is desired to empty a tank, the operator grasps the pipe 20, which has on it the cover member 21 folded in the manner illustrated in Figure 4. The pipe is then inserted through the opening 14 of the tank. The upper end is then secured to the pipe 15. The cord 29 is then untied and the cover member spread out with the hem 22 resting on the 45 head 13 and around the edges of the opening 14, in the manner illustrated in Figure 2.

The collar 21 is elevated to such a point that the sides of the cover will assume a steep inclined position, so that any hot cinders or 50 the like falling on the side of the cover will roll off to position on top of the metal head 13.

If the weather is windy, it may be necessary to weight the hem 22 or apply ropes or 55 cords through the openings 23.

By this arrangement it will be seen that I have provided a very simple and effective cover which is permanently connected to the pipe 20, and which may be easily and quickly 60 placed into operative position, and when so placed all danger of dust and hot cinders entering the tank will be eliminated.

It will further be seen that I have provided a cover which eliminates the objections to the 65 methods heretofore used, :nasmuch as the de-

vice is always accessible and overcomes the tendency of the operator to neglect the duty of covering the opening on account of the time required and the inconvenience in handling a frozen cover.

70 I claim as my invention:

1. In a device of the class described, the combination of a pipe member, a cone shaped cover member formed of pliable fireproof material, and means for binding said cover in a 75 collapsible condition adjacent to said pipe.

2. In a device of the class described, the combination of a pipe member, a cone shaped cover member formed of pliable fireproof material, and means for binding said cover in a 80 collapsible condition adjacent to said pipe, the bottom edge of said cover being provided with perforations, for the purposes stated.

3. In a device of the class described, a cone 85 shaped cover formed of pliable material having an opening in its apex end, a reinforcing collar formed of pliable material for said opening, a metal clamp surrounding said collar for adjustably mounting the same on a pipe, and a binding cord having its central 90 portion attached to said cover.

4. In a device of the class described, a cone shaped cover formed of pliable material having an opening in its apex end, a reinforcing 95 collar formed of pliable material for said opening, a metal clamp surrounding said collar for adjustably mounting the same on a pipe, a binding cord having its central portion attached to said cover, and a series of 100 perforations in the base edge of said cover.
